FISH SCALE SCRAPER

Claude Canion, 91 Tidwell Road, Houston, Tex.

Filed Mar. 31, 1965, Ser. No. 84,529

Term of patent 14 years

(Cl. D9—2)

FIG. 1

FIG. 2

FIG. 3

FIG. 1 is an isometric view showing one side and a top view of a fish scale scraper, showing my new design;

FIG. 2 is a side elevational view showing the other side thereof; and

FIG. 3 is a plan view showing the bottom thereof.

I claim:

The ornamental design for a fish scale scraper, as shown.
